UNITED STATES PATENT OFFICE.

ROBERT SANFORD RILEY, OF WORCESTER, MASSACHUSETTS, ASSIGNOR TO SANFORD RILEY STOKER CO., OF WORCESTER, MASSACHUSETTS, A CORPORATION OF MASSACHUSETTS.

UNDERFEED STOKER.

1,418,831.

Specification of Letters Patent. Patented June 6, 1922.

Application filed August 4, 1919. Serial No. 315,167.

To all whom it may concern:

Be it known that I, ROBERT SANFORD RILEY, a citizen of the United States, residing at Worcester, in the county of Worcester and State of Massachusetts, have invented 5 a new and useful Underfeed Stoker, of which the following is a specification.

This invention relates to an underfeed stoker of the type in which the retort side 10 walls are laterally movable.

It is the principal object of my present invention to provide improved operating mechanism for reciprocating the side walls of the retort, such mechanism preferably deriving 15 motion from the coal feeding plunger. Connections may also be provided for reciprocating the retort bottom plate longitudinally of the retort. A feature of my invention also relates to the provision of connections where- 20 by the relative movement of the side walls and the retort bottom plate may be adjusted as desired.

Other features of my invention relate to a device for lifting and spreading the fuel 25 at the rear end of the retort, and to certain arrangements and combinations of parts which will be hereinafter described, and more particularly pointed out in the appended claims.

30 A preferred form of my invention is shown in the drawings in which—

Fig. 1 is a longitudinal sectional elevation of my improved stoker;

Fig. 2 is a transverse sectional elevation 35 taken along the line 2—2 in Fig. 1;

Fig. 3 is a partial plan view with the retort side wall and overfeed grate sections removed;

Fig. 4 is a plan view of two of the side 40 wall and overfeed grate sections;

Figs. 5 and 6 are partial longitudinal sections taken along the lines 5—5 and 6—6 in Fig. 2;

Fig. 7 is a partial side elevation, looking 45 in the direction of the arrow 7 in Fig. 2;

Fig. 8 is a partial plan view of a slight modification, and

Fig. 9 is a sectional view on the line 50 9—9 in Fig. 1.

Referring to the drawings, I have shown 55 my improved underfeed stoker as comprising a hopper 10 adapted to supply coal to a cylindrical passage 11, within which a coal feeding plunger 12 is reciprocated in any convenient manner, as by a piston 13 con-

nected to the plunger 12 by a piston rod 14 and reciprocated in a cylinder 15 by compressed air, steam, water, or other suitable operating medium. It will be understood that the specific means used for actuating 60 the plunger 12 may be varied to suit the conditions of operation.

The passage 11 has a rearwardly enlarged opening 16 through which the coal is fed to the retort by the plunger 12. The side 65 walls of the retort are formed of laterally moving members 17, each comprising a retort side wall portion 18, an overfeed grate 19, and preferably a discharge plate 20.

These collective members forming retort 70 sections 17 are successively disposed longitudinally of the retort in opposed pairs, and provision is made for alternately reciprocating adjacent sections 17. As shown in Figs. 2 and 3, the opposed members of each 75 pair are also arranged to alternately approach and recede from each other.

The discharge plates 20 are pivoted at 21 to the outer ends of the retort sections 17, and extend outward and downward from their pivots. The plates 20 are preferably also supported at intermediate points by rolls 22 mounted on arms 23 fixed to a shaft 24 which in turn is suitably mounted in bearings in the frame of the stoker. The 85 arms 23 are manually adjustable to raise and lower the rolls 22 as desired. In this manner the openings between the outer ends of the discharge plates and the side walls 24 may be suitably adjusted to the fuel and 90 to the state of combustion in the furnace.

The retort is provided with a longitudinally movable retort bottom plate 26 (Fig. 1) the rear end of which is covered by a wedge or plow-like member 27 (Fig. 9) 95 fixed to the rear end of the retort, and adapted to raise and spread laterally such fuel as reaches the rear end of the retort.

For alternately reciprocating adjacent retort sections, I provide three-armed levers 28 (Figs. 2 and 6) pivoted at 29 to the frame of the stoker.

The longitudinally extending arms of the levers 28 extend upwardly to form studs 30 and 31 fitting suitable openings in the 105 under side of the retort sections 17.

The rounded ends 32 of the inwardly extending third arms of the levers 28 are received in recesses 33 in a bar 34, mounted for longitudinal reciprocation beneath the 110

bottom plate 26. One of the bars 34 is provided at each side of the retort to operate the retort sections on one side thereof.

The two bars 34 are connected by a cross head 35 (Fig. 1) to which is firmly secured a post 36, in which is threaded a bolt or headed stud 37 extending through an arm 38 fixed to the plunger 12 and movable therewith. A lug 39 on the underside of 10 the retort bottom plate 26 also supports a post 40 in which is threaded a bolt or stud 41 likewise extending through the arm 38.

As the arm 38 moves with the plunger 12, it engages the posts 36 and 40 at one 15 end of its path of travel, and the heads of the studs 37 and 41 at the opposite end of its travel, thus having a lost-motion connection by which the plate 26 and bars 34 are reciprocated, for relatively shorter distances. The amount of lost-motion may be 20 reduced by placing removable collars 42 on the studs 37 and 41 as indicated in Fig. 1. In this way, the relative movement of the plate 26 and bars 34 may be varied as desired.

In Fig. 8 I have shown a slightly-modified arrangement of the levers 28 by which opposite retort sections will move simultaneously in the same direction to the right or 30 to the left, maintaining a substantially constant distance between them, while alternate successive sections will move in opposite directions as in the form previously described.

35 For a more complete description of the structure of the retort sections and the functions of the section parts, reference is made to my co-pending application Serial No. 315,165 filed herewith. It will be understood 40 that the space beneath the retort is enclosed to form an air chamber to which air under pressure may be admitted through a damper-controlled opening 43 and from which air at reduced pressure may be admitted 45 by dampers 44 to the overfeed grate portions 19 of the retort sections.

Having thus described my invention, it will be evident that changes and modifications can be made therein by those skilled in 50 the art, within the spirit and scope of my invention as set forth in the claims, and I do not wish to be otherwise limited to the details herein set forth, but what I do claim is:

55 1. An underfeed stoker, having, in combination, a retort having side walls formed in sections successively disposed along said retort, and means to alternately reciprocate adjacent sections, said means comprising a 60 bar reciprocated longitudinally of said retort, and a plurality of levers engaged thereby, said levers being directly connected to

said side wall sections and effective to alternately reciprocate said sections.

2. An underfeed stoker, having, in combination, a retort having side walls formed in sections successively disposed along said retort, and means to alternately reciprocate adjacent sections, said means comprising a bar mounted for movement longitudinally 70 of said retort, means to move said bar, means to adjust the extent of such movement, and a plurality of levers engaged by said bar and each directly connected to move a pair of adjacent wall sections simultaneously in 75 opposite directions.

3. An underfeed stoker, having, in combination, a retort having side walls formed in sections successively disposed along said 80 retort, and means to alternately reciprocate adjacent sections, said means comprising a plurality of levers mounted on fixed pivots, a bar engaging said levers, and means to reciprocate said bar longitudinally of said retort, each lever having upwardly extended 85 connections to a pair of adjacent wall sections and being effective to reciprocate said sections simultaneously in opposite directions.

4. An underfeed stoker, having, in combination, a retort having side walls formed in sections successively disposed along said retort, and means to alternately reciprocate adjacent sections, said means comprising a three-armed lever for each pair of adjacent 95 sections, means to connect opposite lever arms to adjacent sections, and a reciprocating member engaging the third arm of said lever to oscillate said lever and reciprocate said sections.

5. An underfeed stoker having, in combination, a retort having side walls formed in sections mounted for transverse movement, a coal feeding plunger, and lost motion connections between said plunger and said walls, whereby the adjacent sections of the latter are transversely reciprocated alternately in opposite directions during a portion only of the movement of said plunger.

6. An underfeed stoker having, in combination, a retort having a longitudinally movable bottom plate and laterally movable side walls, a coal feeding plunger for said retort, means to reciprocate said plunger, and lost motion connections from said plunger to said bottom plate and to said side walls, whereby reduced motion may be communicated to said plate and to said walls from said plunger during a portion only of the 115 movement of the plunger.

In testimony whereof I have hereunto affixed my signature.

ROBERT SANFORD RILEY.
